UNITED STATES PATENT OFFICE.

WILLIAM BROWN WILSON, OF WELL-HALL, ENGLAND.

MECHANISM FOR OPERATING SINGLE SLEEVE VALVES.

Application filed October 15, 1924. Serial No. 743,735.

To all whom it may concern:

Be it known that I, WILLIAM BROWN WILSON, a subject of the King of England, and a resident of No. 14 Dickson Road; 6 Well-Hall, S. E. 9, in the county of Kent, Kingdom of Great Britain, have invented certain new and useful Improvements in Mechanism for Operating Single Sleeve Valves, of which the following is a specification, reference being had to the accompanying drawings.

The present invention relates to mechanism for operating single sleeve valves of internal combustion engines, steam engines 15 and the like, a principal object of the invention being to provide for this purpose a simple form of mechanism which is positive in action and effective to oscillate the sleeve valve in one direction during the induction or inlet stroke of the piston, to then return the valve to and permit it to remain in normal position, that is, the position in which the inlet and exhaust ports of the engine are closed, during the compression 25 power strokes of the piston, to then oscillate the valve in the opposite direction during the exhaust stroke of the piston and finally return it to normal position, thus completing one cycle of operation.

30 A further object of the invention is to provide a valve operating mechanism of the character aforesaid which is capable of adjustment to vary the time of opening and closing of the inlet and exhaust ports in conformity with the speed of the engine or for other purposes as may be desired.

Further objects, advantages and novel features of design, construction and arrangement comprehended by the invention will 40 be apparent as the nature thereof is better understood from the following description of one embodiment of the invention which I have illustrated on the accompanying drawings forming a part hereof.

45 While the invention is adapted for employment in various forms of sleeve valve engines, it particularly lends itself to use in connection with a sleeve valve of the type disclosed and claimed in and which forms 50 the subject of an application for Letters Patent of the United States executed by me of even date herewith and entitled "Improvements in single sleeve valves for internal combustion engines, steam engines 55 and the like" and in the said drawings I have therefore shown and will now proceed

to describe a form of the invention embodied in an internal combustion engine of the character shown in said application.

In the accompanying drawings Fig. 1 is 60 a fragmentary vertical central section through the cylinder of an engine of the character aforesaid and embodying valve actuating mechanism constructed in accordance with the present invention, certain of 65 the parts being shown in elevation and, Fig. 2 is a top plan view thereof. Fig. 3 is an enlarged fragmentary elevation of a portion of the cam shaft and adjacent parts and Fig. 4 is an end view thereof. Fig. 5 is a 70 fragmentary bottom plan view on a reduced scale of the parts shown in Fig. 4 in normal position and Figs. 6 and 7 are similar views showing the positions of the cam rollers at the respective extremities of their oscillatory movement. Like numerals are used to designate the same parts in the several figures. 75

As shown, and as more fully disclosed in my said application, the engine embodies the 80 usual cylinder block 1 disposed on a crank case 2 which encloses the crank shaft 3 connected by the connecting rod 4 with a piston 5 in the usual manner, the cylinder block being arranged to provide a space or chamber 6 for the circulation of cooling water and the interior of the block being bored out to form the cylinder 7 in which is disposed a sleeve valve 8 having an inwardly curved head terminating in a spindle 10 extending 85 through the cylinder head 11, provided with an internal chamber 12 for the circulation of cooling water, the sleeve valve 8 being rotatable within the cylinder and provided in its head with ports 13 adapted to register with 90 ports 16 and 17 formed in the cylinder head. Through these latter ports, when the ports in the sleeve are properly aligned therewith, the fresh gases can be drawn into the interior of the sleeve which forms the combustion chamber of the engine on the inlet stroke of the piston and exhausted from 95 the interior of the sleeve on the exhaust stroke of the piston. As these several parts are more fully disclosed in said application 100 reference thereto may be had for a more extended description thereof and of their method of operation if required. 105

In the operation of an engine of the aforesaid character it is requisite that oscillation 110 of the sleeve 8 be effected in opposite directions and at suitably timed intervals with

respect to the movement of the piston so as to bring the ports 13 into registry with the different ports in the head to permit the fresh mixture to be drawn into the cylinder on the intake stroke of the piston and the burned mixture or exhaust to be discharged therefrom on the exhaust stroke of the piston, and further, that the sleeve be maintained in a position during the compression and power strokes of the piston such that the ports in the sleeve are out of registry with all of the ports in the head, and for effecting these results I may, in accordance with the present invention, provide mechanism of the following character for actuating the sleeve.

Within the crank case and extending parallel to the crank shaft I provide a cam shaft 20 supported in suitable bearings and driven from the crank shaft in any convenient way as by gearing, silent chain or the like and preferably at one-half the speed of the crank shaft. The cam shaft is provided for each cylinder of the engine with a pair of longitudinally spaced cams 21, 22 which are respectively operative to actuate cam rollers 23 and 24 the faces of which may be slightly arcuate if desired instead of flat. These rollers are mounted for rotation upon the opposite ends of a pin 25 which in turn is fixed in the lower end of an offset lug 26 disposed at the lower end of a spindle or shaft 27, the rollers being held on the end of the pin in any suitable way as, for example, by pins or keys 28 driven through the pin. The spindle 27 is rotatably mounted in vertical position alongside of or in the cylinder block and supported in suitable bearings and preferably in such manner as to prevent any material longitudinal play, the upper end of the spindle terminating at a convenient distance above the cylinder head.

The several parts just described are so arranged that the peripheries of the rollers adjacent the cams are tangent to a vertical plane parallel to and passing through the axis of the spindle 27 and the upper end of the spindle is suitably connected with the projecting end of the spindle 10 of the sleeve valve. While this connection may be formed in any suitable manner it may be conveniently accomplished by providing the upper end of the spindle with a gear or gear segment 29 arranged to mesh with a gear or gear segment 30 disposed on the end of the spindle 10 and pinned or otherwise secured thereto so as to turn therewith, gear 29 being similarly secured to the end of the spindle 27.

As in the operation of sleeve valves of the character disclosed in my said application it is desirable that the valve be given a positive movement of some 31° in either direction from its normal or closed position, I

prefer to arrange the connection between the two spindles in such manner that the rotative movement of the spindle 27 requisite to effect the necessary rotative movement of the sleeve shall take place through a lesser angle than that through which the sleeve is turned, and I effect this result by suitable design of the ratio between the gears 29 and 30. Thus I may arrange these gears in a ratio of 2:1 substantially as shown in the drawings so that a movement of the spindle 27 through a given angle XYZ, will turn the sleeve through an angle AOB which is twice as great as the angle XYZ, but it will of course be apparent that any other ratio may be employed so as to give a greater or less motion to the sleeve for a given movement of the spindle according to the amount of port opening or area which is desired.

The cams 21 and 22 are so formed that during one revolution of the cam shaft 20 the spindle 27 will be oscillated in one direction during the induction or inlet stroke of the piston so as to turn the sleeve valve to a position to open the inlet ports and allow the charge to be drawn into the combustion chamber, then returned to normal position so as to close both the inlet and exhaust ports during the compression and power strokes of the piston, then oscillated in the opposite direction so as to open the exhaust ports during the exhaust stroke, and then finally returned to normal position, thereby completing one cycle of operations.

It will thus be apparent that I have provided simple and efficient mechanism for effecting oscillation of the sleeve valve adapted for employment in single cylinder and multi-cylinder engines for effecting a positive movement of the sleeve under operative conditions.

While I have herein illustrated and described one form of my invention with considerable particularity and in connection with a sleeve valve engine of the type disclosed and claimed in my said application for U. S. Letters Patent, I do not thereby desire or intend to confine myself to the use of said mechanism solely to engines of that type, nor, irrespective of the particular type of engine in which it is employed, to any specific design, construction or arrangement of the various parts of the mechanism as the same are capable of material modification from the precise embodiments to which I have referred without departing from the spirit and scope of the invention as defined in the appended claims.

Having thus described my invention, I claim and desire to protect by Letters Patent of the United States:

1. The combination with an engine having a sleeve valve, of valve actuating means comprising a cam shaft having a pair of cams for each cylinder of the engine, a

- roller cooperative with each of said cams, a rotatable spindle, means for rotatably supporting the rollers adjacent one end of the spindle and on opposite sides of its axis, and means connecting the other end of the spindle with the sleeve valve of the engine.
2. The combination with an engine having a sleeve valve, of valve actuating means comprising a cam shaft having a pair of longitudinally spaced cams for each cylinder of the engine, a cam roller cooperative with each cam, a spindle extending at right angles to the axis of the cam shaft, means carried by the spindle for rotatably supporting the rollers on opposite sides of the axis of the spindle for coaction with the cams, and means connecting the spindle with the sleeve valve of the engine and operative to oscillate said valve in conformity with the rotative movement of the spindle.
3. The combination with an engine having a sleeve valve, of valve actuating means comprising a cam shaft having a pair of cams for each cylinder of the engine, a rotatable spindle extending normal to the axis of the cam shaft, a pair of rollers, and means for supporting the rollers in axial alignment with each other and in offset relation to the axis of the spindle.
4. The combination with an engine having a sleeve valve, of valve actuating means comprising a cam shaft having a pair of cams for each cylinder of the engine, a rotatable spindle extending normal to the axis of the cam shaft, a pair of rollers, and means for supporting the rollers in axial alignment with each other and in offset relation to the axis of the spindle with the peripheries of the rollers tangent to a plane parallel to and passing through the axis of the spindle.
5. The combination with an engine having a sleeve valve, of valve actuating means comprising a cam shaft having a pair of cams for each cylinder disposed in longitudinally spaced relation on the shaft, a rotatable spindle or shaft extending normal to the axis of the cam shaft and having an offset lug adjacent one end, a pin carried by the lug and having its axis disposed in a plane normal to the axis of the spindle and passing through the axis of the cam shaft, and a roller rotatably mounted on each end of the pin and cooperative with the adjacent cam on the cam shaft.
6. The combination with an engine having a sleeve valve, of valve actuating means comprising a cam shaft having a pair of cams for each cylinder disposed in longitudinally spaced relation on the shaft, a rotatable spindle or shaft extending normal to the axis of the cam shaft and having an offset lug adjacent one end, a pin carried by the lug and having its axis disposed in a plane normal to the axis of the spindle and passing through the axis of the cam shaft,
- and a roller rotatably mounted on each end of the pin and cooperative with the adjacent cam on the cam shaft, the faces of said rollers lying tangent to a plane parallel to and passing through the axis of the spindle.
7. The combination with an engine having a sleeve valve, of valve actuating means comprising a cam shaft having a pair of cams for each cylinder disposed in longitudinally spaced relation on the shaft, a rotatable spindle or shaft extending normal to the axis of the cam shaft and having an offset lug adjacent one end, a pin carried by the lug and having its axis disposed in a plane normal to the axis of the spindle and passing through the axis of the cam shaft, a roller rotatably mounted on each end of the pin and cooperative with the adjacent cam on the cam shaft, the faces of said rollers lying tangent to a plane parallel to and passing through the axis of the spindle, and means connecting the other end of the spindle with the sleeve valve and operative to oscillate said valve in conformity with the movement of the spindle.
8. The combination with an engine having a sleeve valve, of valve actuating means comprising a cam shaft having a pair of cams for each cylinder disposed in longitudinally spaced relation on the shaft, a rotatable spindle or shaft extending normal to the axis of the cam shaft and having an offset lug adjacent one end, a pin carried by the lug and having its axis disposed in a plane normal to the axis of the spindle and passing through the axis of the cam shaft, a roller rotatably mounted on each end of the pin and cooperative with the adjacent cam on the cam shaft, the faces of said rollers lying tangent to a plane parallel to and passing through the axis of the spindle, and means connecting the other end of the spindle with the sleeve valve and operative to oscillate the valve through a different angle than that through which the spindle is rotated through coaction of said rollers and said cams.
9. The combination with an engine having a sleeve valve, of valve actuating means comprising a cam shaft having a pair of cams for each cylinder disposed in longitudinally spaced relation on the shaft, a rotatable spindle or shaft extending normal to the axis of the cam shaft and having an offset lug adjacent one end, a pin carried by the lug and having its axis disposed in a plane normal to the axis of the spindle and passing through the axis of the cam shaft, a roller rotatably mounted on each end of the pin and cooperative with the adjacent cam on the cam shaft, the faces of said rollers lying tangent to a plane parallel to and passing through the axis of the spindle, and means connecting the other end of the spindle with the sleeve valve and operative to os-

cillate the valve through twice the angle through which the spindle is rotated through coaction of said rollers and said cams.

- 6 10. The combination with an engine having an oscillatory sleeve valve, of means for actuating said valve comprising a cam shaft, a rotatable spindle extending normal to the axis of the cam shaft, a pair of cams on the shaft disposed on opposite sides of the axis of the spindle, a roller adapted for cooperation with each cam, means for supporting the rollers from the spindle on opposite sides of its axis and in offset relation with respect thereto, and means interposed between the spindle and the valve operative to transmit the motion of the spindle to the valve as the spindle is oscillated through the coaction of said rollers with said cams.
- 10 15. means interposed between the spindle and the valve operative to transmit the oscillatory motion of the spindle to the valve.

11. The combination with an engine hav-

ing an oscillatory sleeve valve, of menas for actuating said valve comprising a cam shaft, 20 a rotatable spindle extending normal to the axis of the cam shaft, a pair of cams on the shaft disposed on opposite sides of the axis of the spindle, a roller adapted for cooperation 25 with each cam, means for supporting the rollers from the spindle on opposite sides of its axis and in offset relation with respect thereto, and means interposed between the spindle and the valve operative to transmit the motion of the spindle to the valve as the spindle is oscillated through the coaction of said rollers with said cams.

In witness whereof, I have hereunto set my hand this 2nd day of October, 1924.

WILLIAM BROWN WILSON.
